UNITED STATES PATENT OFFICE.

HERBERT DAVENPORT, OF PATERSON, NEW JERSEY.

LEASE-FORMING MECHANISM FOR WARPING-MILLS.

SPECIFICATION forming part of Letters Patent No. 500,097, dated June 20, 1893.

Application filed February 14, 1893. Serial No. 462,251. (No model.)

To all whom it may concern:

Be it known that I, HERBERT DAVENPORT, a citizen of the United States, residing at Paterson, in the county of Passaic and State of New Jersey, have invented certain new and useful Improvements in Lease-Forming Mechanism for Warping-Mills; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to a new and improved construction of reed and also the use of two reeds in a frame at one time for the purpose of more readily separating the filaments, either single or double, without the necessity 20 of separating and lifting the strands by hand, or changing the reeds such methods being the only operations used at the present time.

Besides enabling a more perfect and rapid separation and lifting of the strands, my invention makes it possible for an inexpert operative to perform the operation which now under the method in vogue requires good eye sight and a long course of training, as the warp being once passed through the reeds 30 there is no necessity for releasing or removing them, because the reeds being arranged for single or double cross warps, the warps can be cut off as made and bobbins placed upon the creel board, as they are unwound or can 35 be replaced by others of a different color by simply drawing the ends through the reeds when joined or knotted.

It is obvious that the reeds being spaced with respect to the dents, either for single or 40 double filaments, any error by the operative is avoided, for only those strands absolutely required to be raised are lifted for use, the others being held down a sufficient distance to clearly separate them. These objects I attain by the mechanism hereinafter more fully 45 described in the specification and illustrated in the accompanying drawings.

In the drawings Figure 1 is a part front view of a reed with dents arranged for a single filament lift. Fig. 2 is a part front view of a reed with dents arranged for a double filament

lift. Fig. 3 is a cross section of a pair of reeds of my construction held in a frame and back to back both being down. Fig. 4 is a cross sectional view of the same with one of the reeds 55 lifted for single filaments, and Fig. 5 is a similar cross sectional view with the other reed lifted for double filaments, the one for single filaments being lowered.

Similar letters in the drawings have reference to similar parts.

I will now proceed to describe the construction and manner of using my newly improved reed for warping mill used in textile manufacture, and my improved method of separating and crossing the filaments, either single or double, in warping.

A in Fig. 1 represents a reed of usual construction for single filaments, having the usual frame —*a'*— in which the dents —*d*— are secured by the wire —*a*— soldered together in the usual manner. The dents —*d*— are soldered together in pairs by the blocks —*b*— thus dividing the dents so joined into a central opening —*e*— and upper and lower spaces. 75 The surrounding frame projects somewhat in front of the dents to give the necessary rigidity but the back of both frames and dent bars are perfectly flush as shown in Figs. 3, 4, and 5.

In Fig. 1 the dents are so united by the blocks —*b*— that in the center of the reed longitudinally, a row of eyes or openings —*e*— is formed which alternate throughout the length of the reed with spaces —*k*— open 85 from the top to the bottom of the frame —*a'*—. Fig. 2 illustrates a reed —*B*— of similar construction arranged for a double filament and has three dent bars —*c*— soldered together by the blocks —*f*—, the dent bars 90 —*c*— forming when united the center double eyes —*e'*— and the two vertical slits or openings —*k'*— alternating therewith in groups of two. The tops of the frames of the reeds are provided with handles or rings or any other 95 suitable device for the purpose of raising or lowering them when necessary. The back of this double reed is as stated flat and level so that when placed in position in the frame —*D*— as shown in Figs. 3, 4 and 5, the backs 100 of the reeds —*A*— and —*B*— are in perfect sliding contact and the dent bars —*d*— of

the reed —A— touch the dent bars —c— of the reed —B—, so as to leave no opening for the warp filament to get between during the process of drawing in or filling the reeds with the warp —W—.

The open frame —D— is so formed as to hold the reeds —A— and —B— together but still allow freedom for a vertical motion. In operation or use the reeds A and B are placed 10 in a suitable frame, as for instance —D— in Fig. 3, the frame D being secured to a stand forming a part of a warping mill of the ordinary construction and secured in the usual manner, not shown in the drawings. The 15 warp W is then drawn in through the dent openings space by space and eye by eye until the whole of the reed is filled or as much as the width of the warp or number of filaments required necessitates, each strand passing 20 through both reeds A and B and alternately through, an eye —e— and opening —k— of the reed A and alternately through a double eye —e'— and two openings —k'— of the reed B. When the warp W is drawn off the 25 bobbins located on a creel board through the reeds A and B a sufficient length, the ends are secured together and fastened to the winding reel in the ordinary manner.

When single filament warp is required the 30 reed A is raised which lifts the alternate filaments as in Fig. 4, leaving the remainder of the warp strands W below. This separation of certain strands or filaments during the process of warping enables a cross of single filaments to be given to the warp during the 35 progress of the process.

In Fig. 5 the single reed A is shown lowered and the double reed raised to form a cross of double filaments in the same manner as that 40 described for the single filament cross, reed A; but in this case the filaments are alternately raised in groups of two. With this arrangement of a double reed held in the frame D as described, it will be seen that instantaneous separation of the strands of the 45 warp may be effected with a degree of certainty, hitherto unattained. This may be more readily appreciated when it is considered that in the present method of crossing or 50 amination, each filament has to be separated and raised by hand clear from its neighboring strand an operation requiring dexterity and skill and always liable to error.

At present in warping the manufacturer 55 uses either a single or double reed through which the warp threads or filaments are passed, to change from a single to a double cross or from a double cross to a single cross the warp threads must be and are cut out and 60 re-threaded through the reed required, either a single or a double one as the case may be, which means a loss of time and a loss of material.

My method of using the combined reeds does 65 away with the necessity of re-threading, as my combined reeds when once threaded are

threaded for all time if desired, as the ends remaining may be tied on to the new ends and drawn through the reeds, in case of a change of warp or a change in the color of the 70 silk or other filaments used in textile manufacture, thereby, as is obvious, saving considerable time and material to the manufacturer which would otherwise be wasted.

My method of separating and crossing 75 threads in warping is as follows. I place a single and a double reed back to back in a suitable frame which admits a vertical motion to be given to the reeds. The single reed is provided with the eyes —e— formed 80 by the blocks —b— which connect the dents —d— and the spaces *k* extending from top to bottom of reed the eyes *e* and spaces *k* being alternate. When the single reed is elevated, as shown in Fig. 4, it separates the warp 85 threads as follows:—The threads passing through the eyes —e— resting upon the lower blocks *b* of said eyes are lifted and the threads passing through the spaces *k* are not elevated; every alternate thread being so elevated and separated from the remaining threads a rod such as is ordinarily used by 90 warpers is passed through the opening thus made between the upper and lower warp threads; the single reed is then lowered and 95 to complete the cross of the single alternate threads, the double reed is raised to the position shown in Fig. 5 on the drawings when the warper will raise all of the warp threads with his rod or hand until the upper blocks 100 —*b*— of the single reed are encountered and said blocks retain every alternate thread or filament, that is every thread which passes through the eyes —e— of the single reed; every other alternate thread or filament being in the spaces *k* of the single reed passes 105 above the upper blocks *b* of the single reed and between the blocks *f* of the double reed, when another rod is inserted by the warper thus forming a complete single filament 110 cross or lease. The method of forming a cross of double filaments is similar to that of making a single cross, with the exception that, the double reed may be first lifted as is shown in Fig. 5, in which figure the double 115 eyes of the double reed separate the warp W by lifting every two alternate strands or filaments, the other groups of two filaments passing through the spaces *k'* of the double reed not being raised. A rod is then inserted 120 between the upper and lower groups of two filaments and the double reed is lowered as in Fig. 3. The single reed is then elevated to the position shown in Fig. 4 when all of the warp threads are elevated by means of a rod or 125 with the hand, the warp strands that are in the spaces *k'* of the double reed passing up above the upper blocks *f* of the double reed B, the upper blocks *f* of the reed —B— retaining and not permitting the filaments passing 130 through the double eyes of the double reed to be elevated. Thus the alternate groups of

two filaments that were on the bottom when the strands were first separated pass above the alternate groups of two filaments which in the first separation were elevated by the lifting 5 of the double reed and the cross of the alternate groups of two filaments being complete another rod is inserted and the single reed lowered as in Fig. 3.

While the crossing of a single filament and 10 the crossing of double filaments are the most usual and ordinary crosses that are made in weaving it is quite evident that my idea of associating two reeds together in warping for the purpose of changing the cross of the threads or 15 filaments as desired, embraces not only single and double reeds, but reeds whose dents are so connected as to form eyes which will carry any number of threads or filaments passed through them above or below the plane or position occupied by the filaments or threads 20 not passing through said eyes but through the eyes or spaces in the adjoining reed, enabling the operative to make a cross of as many threads as desired, the reeds being constructed so as to have the requisite number 25 of eyes to carry the warp thread or filament as aforesaid. I shall therefore in my claims ask to be protected in the associating together of two reeds for warping, so construct-

ed as to cross as many threads or filaments 30 as desired.

Having described the construction and use of my newly invented device or reed for warping purposes, what I claim as new, and desire to secure by Letters Patent, is as follows:

35

1. A frame, a reed provided with single openings and having a level and smooth-faced back, a reed provided with double openings and also having a level and smooth faced back, the single and double reeds being 40 placed back to back in sliding contact in said frame, substantially as shown and described and for the purposes specified.

2. A frame, a reed mounted in said frame to move up and down therein, which reed has 45 single openings, a second reed also mounted in the same frame adjacent to the first reed and to move up and down, this second reed having double openings, all constructed substantially as set forth.

50

In testimony whereof I affix my signature, in the presence of two witnesses, this 10th day of February, A. D. 1893.

HERBERT DAVENPORT.
